(57) **CLAIM**

The ornamental design for an automatic hair curler, as shown and described.

DESCRIPTION

FIG. 1 is a front elevational view of an automatic hair curler embodying my new design;

FIG. 2 is a left-side elevational view thereof;

FIG. 3 is a top plan view thereof;

FIG. 4 is a bottom plan view thereof;

FIG. 5 is a right-side elevational view thereof; and,

FIG. 6 is a front, bottom and right-side perspective view thereof.

The evenly spaced broken lines illustrate portions of the automatic hair curler. The dash-dot-dash broken lines illustrate the bounds of the claimed design. The broken line disclosures form no part of the claimed design.
